UNITED STATES PATENT OFFICE.

EMORY S. ENSIGN, OF NEW YORK, N. Y.

DRIVE FOR CALCULATING-MACHINES.

1,331,561.

Specification of Letters Patent. Patented Feb. 24, 1920.

Application filed March 10, 1916. Serial No. 83,401.

To all whom it may concern:

Be it known that I, EMORY S. ENSIGN, a citizen of the United States, residing at New York city, New York, have invented an Improvement in Drives for Calculating-Machines, of which the following description, in connection with the accompanying drawing, is a specification, like characters on the drawing representing like parts.

10 This invention relates to an improvement in calculating machines and more particularly to driving mechanism adapted to be used in such machines.

15 It is common at present to employ a spring motor to rotate the meter or indicia-bearing means upon which the numerical results are displayed to the operative as the necessary torque is not readily built up by the small electric motors available for this 20 purpose and, furthermore, the strain of the constant starting under the maximum load is highly detrimental to this type of power source. Such spring motor is automatically re-wound, when its tension drops below a 25 predetermined point, by the intermediary of an electric motor.

30 In this improvement an electric motor or other power means is employed, and, during the operation of the calculating machine, the power source runs continuously. The transmission of the power is effected through the interposition of a novel driving mechanism and clutch. It was found undesirable to employ a clutch which throws the 35 power into and out of engagement sharply, as the resultant rebound or jump of the meter or numeral-bearing wheels entails liability to inaccuracies in the arithmetical results. Therefore, there has been produced 40 a drive and transmission which very suddenly accelerates to a direct drive and which, when thrown out of engagement with the power source, effectually prevents backlash or rebound in the driven members.

45 An object of this invention is to provide an efficient driving mechanism for calculating machines.

50 Another object is to provide a drive and clutch mechanism which will obviate the jump and rebound of the index wheels or meter.

55 A further object is to reduce the size and construction cost and lighten the weight, and to produce a machine quiet in operation.

55 Other objects of the invention will more fully appear from the following description

and the accompanying drawings and will be pointed out in the annexed claims.

In the drawings,

Figure 1 is a side elevation of the novel 60 clutch and drive as applied to a calculating machine;

Fig. 2 is a section on the line 2—2 of Fig. 1;

Fig. 3 is a section on the line 3—3 of 65 Fig. 2.

In this selected embodiment of the invention disclosed in the accompanying drawings, the machine is inclosed in a suitable casing 1, aluminum being the material preferably employed in order to keep the weight of the machine as low as compatible with efficiency and durability. The shaft 2, which carries the numeral index wheel composing the meter upon which the arithmetical result is suitably displayed to the operative, is journaled in the casing 1. One of the journals is shown in section in Fig. 2. They consist each of a standard 3 having an offset portion affording a bearing 4 for the 70 shaft 2. The casing 1 has, preferably, similar end slots 5, one being shown in Fig. 2. The slots receive the shaft end portions in the assembling of the incased machine. The clutch means is disposed between the drive 75 and the meter in this selected embodiment. It has heretofore been customary to have a clutch or stop-motion at the end of the shaft opposite the drive. Defects in this construction developed in that the whole meter-bearing shaft between the clutch and drive was subject to torsional displacements due to the shaft flexibility and to the inertia or to the momentum of the parts attendant upon sudden starting and stopping. The 80 85 90 95 result was that the meter or index wheels often jumped past the correct indications rendering the machine inaccurate. Herein, the maximum play of shaft torsional strain is confined substantially to one end of the 100 shaft, viz., that included between the drive and the clutch which members in this selected embodiment are positioned relatively close together at one end of the shaft.

The driving mechanism here disclosed 105 may be employed in various modes but, is in this embodiment incorporated in a calculating machine. Herein, an indicator-bearing shaft is under constant torque transmitted thereto through the intermediary of a pair 110 of members, one of which is constantly driven from a suitable power source and is

in constant frictional engagement with the other, the latter being secured to and revolute with the shaft. A clutch member is fixedly secured to the shaft and, while so constructed to have its revolution normally prevented, it is releasable at will.

This embodiment of this novel drive and clutch has a driving mechanism, located without the machine casing 1, which comprises a pulley 6 (Fig. 1) having its hub 7 loosely mounted upon the shaft 2, and revoluble independently thereof. The member 6 may be actuated through any suitable transmission media such as toothed or friction gears. Such media is simply provided by means of the ordinary belting and, to this end, the body 8 of the pulley bears a peripheral flange 9 which is preferably annularly recessed to receive a belt 11. The belt 11 is actuatable by any suitable power source and, as shown, is driven by the electric motor 12 mounted upon a pivoted bracket 10 secured to the machine casing 1. The turnbuckle 13, movable in bosses on the motor and machine casings, respectively, functions as a means for tightening the belt 11 through the movement of the motor in an arc about its pivotal mounting. A disk 14 is secured to the shaft 2 by means of the pin 15 and is revoluble with the shaft. The pulley upon its inner face carries means for engaging frictionally the disk 14 by which means a turning moment is constantly imparted to the shaft 2.

In this embodiment of the invention, the disk 14 is composed of a metallic substance, preferably steel, and its face, presented to the pulley friction means, is highly polished. The frictionally engaging means of the pulley comprise a plurality of small washers, disks or plates 16, three being shown in this embodiment. These plates are preferably circular in form and are secured, substantially equi-distantly, upon the inner pulley face by means of any suitable fastenings such as rivets 17. Each plate is held against any tendency to rotatory movement about its rivet by means of a pin 18. These plates may be formed of any suitable substance but it has been found that what is known in the trade as arguta wood functions efficiently for this purpose. This wood is a rock maple or similar wood treated with a wax or oily substance and is commonly used for self-lubricating bearings. The plates 16 are preferably tensionally held against the polished face of the disk 14 by means of a spring functioning to push inwardly the pulley upon the shaft. Such spring 19 may be of the coiled type, and is retained within a cap 20 fitted over the end of the shaft and held against dislodgment by means of the pin 21. The pulley end of the spring bears against a preferably hardened and polished washer 22 interposed be-

tween the pulley and the spring. This washer serves to counteract friction induced by relative movement between the shaft and the pulley. The tension of the spring against the pulley, and hence of the contact of the pulley plates and the disk face, may be increased or diminished as desired by the interposition of one or more similar washers 23 in the cap between the spring end and the head of the cap inside, or by increasing the number or thickness of the washer 22. The efficient tension of the spring having been once fixed, the wear of the parts being very slight, it is deemed preferable to make this construction "fool-proof" by having the pin 21 countersunk in the cap 20. To the average operative, apparently the spring cap cannot be removed and the tension altered except by demounting a large portion of the machine; but, the cap is readily removed by inwardly pushing the cap against the tension of the spring when the pin 21 is readily removed from the shaft aperture.

A constant torque is thus normally imparted to the shaft 2. A stop or clutch member is interposed upon the shaft 2 between the drive and the meter comprising the usual index wheels which are not necessary to be shown. The function of this clutch member is normally to hold the shaft 2 against revolving. It is so constructed that revolution of the shaft may readily be permitted as desired. A disk 24 is mounted upon the shaft 2 and is held revoluble with the shaft by the pin 25. An arm 26 is secured by the screw 27 to the face of this disk which is toward the drive end of the shaft. This arm has a terminally offset portion or shoulder 28 which is normally engaged by a stop which prevents movement of the disk. This stop member is movable to release the disk arm by means of a system of levers actuated by the usual adding bar of the calculating machine. A set of levers to control the release of the clutch disk is shown in the drawings though obviously they may be of any type effecting the desired disk-controlling function. In the embodiment here illustrated, the arm 29 is pivotally mounted on the casing. The lower end of this arm is preferably forked, having two lateral arms terminally offset and forming the shoulders 30. In normal position the shoulder adjacent the disk projects within the path of traverse of the arm 26 and prevents movement of the disk and shaft. The end portion 31 of a bell crank lever, similarly pivotally mounted is received between the two shoulders 30. A spring 32 secured to the opposite arm 33 of the bell crank lever and to the casing 1, normally tends upwardly to push this arm 33 and hence inwardly to hold the shoulder 30 in the path of the shoulder 28 of the disk arm 26. The usual adding bar 34

on the front of the calculating machine is mounted so that upon its manual depression, its boss 35 will depress the arm 36 of a pivoted bell-crank lever. The arm 37 of 5 such lever, contacting with the arm 33 will depress the latter against the tension of the spring 32. Thus, upon the depression of the bar 34, the pivoted arm 29 is withdrawn.

10 In operation the device is simple, efficient, durable and overcomes effectively the disadvantages of the present drive. When it is desired to permit the revolution of the shaft 2 in order to cause the meter or index 15 wheels to function, the adding bar 34 is downwardly pressed. This force transmitted through the lever system effects the withdrawal of the shoulder 30 from engagement with the shoulder 28 of the disk 20 arm 26. The disk 24 and shaft 2 are then freely revoluble under the torque constantly imparted to the shaft by the novel driving mechanism herein. The "pick-up" or acceleration is certain and rapid and without 25 jar, jump or noise, nor is an electric motor over-taxed by a sudden load, as the load on the power source is substantially constant. When the key-bar is depressed, it is immediately released so that the shoulder 30, 30 under the indirect action of the spring 32, immediately resumes its place in the path of the shoulder 28 of the disk arm. The revolution of the shaft having been completed, the further movement is arrested 35 by the engagement of the disk arm and the stop or arm 29. The stoppage of the shaft is certain and without rebound or back-lash as the turning force is still applied to the shaft and holds the shaft immovable with 40 the disk arm against the stop.

There is thus provided an efficient, simplified clutch and drive adaptable to various uses and which when used in a calculating machine will prevent jump of the meter at the start or rebound at finish of its working traverse.

Should any part of the mechanism become jammed it is obvious that when the resistance to shaft revolution passes a pre- 50 determined point the shaft may rest immovable and injury to the parts avoided. The construction costs have been lowered, the weight lightened and noise of operation reduced to a modicum.

55 It is to be understood that the construc-

tion disclosed herein is illustrative but not restrictive and that the same may be modified within the meaning and scope of the claims which follow.

Having fully described my invention, 60 what I claim as new and desire to secure by Letters Patent is:

1. A driving mechanism comprising a driving element, a driven member having a smooth bearing face, a plurality of frictional, self-lubricating plates radially and equidistantly secured to said driving element, means tensionably to press the plates toward the driven member whereby the plates frictionally engage said bearing face 65 and impart a constant torque to the driven member, and means normally preventing rotation of the driven member and operable to permit rotation thereof.

2. A driving mechanism comprising a 70 driven disk, a driving element, said disk and driving element having adjacent opposed faces, a plurality of friction devices secured to the face of the driving element and revoluble therewith and severally engaging 75 the face of the disk whereby a constant torque is imparted to the disk, and means normally preventing rotation of the disk and operable to permit rotation thereof.

3. A driving mechanism comprising a 80 driven element, a driving element, one of said elements presenting a plane surface perpendicular to the axis of rotation and opposed to the other element, self-lubricating frictional means secured to the said 85 other element and revoluble therewith and frictionally engaging said plane face whereby a constant torque is imparted to the driven element, and means normally preventing rotation of the driven element and 90 operable to permit rotation thereof.

4. A driving mechanism comprising the construction defined in claim 3 in which the said self-lubricating frictional means is composed of a plurality of radially disposed 100 plates of arguta wood.

5. A driving mechanism comprising the construction defined in claim 3 in which the said self-lubricating frictional means is composed of a plurality of radially disposed plates of wood treated with a suitable wax or oily substance.

In testimony whereof, I have signed my name to this specification.

EMORY S. ENSIGN.
